UNITED STATES PATENT OFFICE.

CLARENCE E. MOODY, OF ZANESVILLE, OHIO, ASSIGNOR OF ONE-FOURTH TO GEORGE F. BRENNER, OF ZANESVILLE, OHIO.

AUTOMATIC SWITCH-THROWER.

No. 921,555.

Specification of Letters Patent.

Patented May 11, 1909.

Application filed May 25, 1908. Serial No. 434,821.

To all whom it may concern:

Be it known that I, CLARENCE E. MOODY, a citizen of the United States, residing at Zanesville, in the county of Muskingum and 5 State of Ohio, have invented certain new and useful Improvements in Automatic Switch-Throwers, of which the following is a specification.

This invention relates to devices for use in 10 connection with railways, whereby a motorman is enabled to throw a switch without leaving his usual position at the front end of the car. The apparatus constituting this improvement is therefore designed primarily 15 for street railway purposes, but it is to be understood that it is not limited in its construction to such use, since it may be employed in connection with the tramways and other forms of railway construction. In de- 20 vices of this character it is essential for the most perfect and satisfactory operation that the motorman or operator of the car shall know positively that the switch is properly thrown, and for this reason there is employed 25 in connection with the operating parts of the device a peculiar form of indicating means, whereby the operation of the device will be determined.

For a full understanding of the invention, 30 including its construction and characteristic advantages, reference is to be had to the following detail description and to the accompanying drawings, in which—

Figure 1 is a plan view of a fragment of the 35 track, switch, and parts associated therewith; Fig. 2 is a partial side elevation of a car equipped with my appliance; Fig. 3 is a front elevation of the parts shown in Fig. 2; Fig. 4 is an enlarged plan, similar to Fig. 1, 40 certain parts being exposed by breaking away; Fig. 5 is a detail of the T-lever, and Fig. 6 is a detail of one of the actuators.

Throughout the following detail description and on the several figures of the drawings similar parts are referred to by like reference characters.

Indicated at 10 is any conventional form of railway having the usual rails 11.

12 is a side track upon which the car may 50 pass when the switch point 13 is thrown to the left in the usual manner.

It is to be understood of course that while there is shown a right switch, the same mech-

anism will be employed for operating a left switch without material alteration.

55

Located at any suitable point between the rails 11 between the approaching car and the switch is a contact member 15 pivoted at 16 intermediate of its ends to a base plate 17. Adjacent the ends of the base plate 17 and 60 parallel with the rails 11 are upwardly extending flanges 18, the forward edges 19 of which are outwardly flared. Attached to or coöperating with the ends of the base 17 are longitudinal track plates 20, which may ex- 65 tend for a considerable distance beneath the ends of the plate and parallel with the rails 11, and which support said flanges 18. The contact member 15 is provided with beveled ends 15', that is to say, the said member is 70 shorter on its front side than on its rear side, so as to provide that the end which projects forwardly shall extend farther laterally across its track plate 20 than that end of the member which at that time will be in the rear. 75 By this construction that end of the contact member which extends forwardly will always be in position to be engaged by a member carried by the car and described hereinafter. The contact member is preferably protected 80 by a cover plate 21 the ends of which are spaced inwardly a sufficient distance from the flanges 18 aforesaid as to allow room for the operating member to engage and operate the contact member. The plate 21 is pro- 85 vided at its ends with curved guide flanges 18' which coöperate with the aforesaid flanges 18 to insure proper engagement between the contact member 15 and the actuator, below described. Extending downwardly from the 90 cover plate 21 is a rear flange 22 and a front flange 23, which flanges substantially inclose the moving parts of the mechanism.

Adjacent to the switch is a T-lever 24 pivoted at 25 to a substantial base 26 located 95 between the rails and preferably attached to the cross ties. Said T-lever comprises right and left arms and a rearwardly extending arm 27, pivoted to which is a connector 28 pivotally connected by any suitable means 100 to the movable members of the switch. The aforesaid right and left members of the T-lever are respectively connected to the outer ends of the aforesaid contact member 15 by means of connections 29, which may be ca- 105 bles or any other suitable form of substantial

connections. As a convenient means for connecting the cables 29 to the T-lever there are provided U-shaped clamps 30. A connection 29 may be held in such U-shaped 5 clamp at any desired adjustment. At their front ends the connections 29 may be attached in any one of a series of holes 31 in the contact member 15. In order to accommodate said connections 29 the rear flange 22 is provided 10 preferably with a plurality of holes or notches 22'. The connections 29 will preferably be inclosed by means of rigid tubes 29' in actual use. In order to indicate clearly to the motorman the position of the switch 15 there is provided a visible indicator immediately operated by said T-lever. The arm 27 extends rearwardly a suitable distance, and its rear end 27' has direct engagement 20 with a switch blade 32. As a convenient means for effecting such engagement the arm 27 at said rear end may be notched, within which notch the front end of the switch blade may engage. The switch box 33 may be located 25 at any suitable point, either between the rails or for instance on a trolley pole. This switch box is equipped preferably with a plurality of differently colored lights, the several colors serving to indicate the various positions which the switch may assume. 30 When the arm 27 is thrown to one side, the switch blade 32 will make connection with such a switch point as will light one of the colored lights. When moved to the opposite side the switch blade will light a differently 35 colored lamp, whereby the motorman will be apprised of the condition of the switch.

Each car will be equipped with one or more simple operating means, under the control of the motorman, whereby he will be enabled to 40 operate the aforesaid switch throwing mechanism without leaving his position. Preferably there will be two of such operating means for each car, whereby the motorman will be enabled to either throw the switch in 45 order that he may pass upon the siding, or else by the operation of the other he will restore to its normal position a switch previously thrown. Each of said operating means will comprise the following essential 50 elements: An actuator 34 movable substantially vertically in a guide 35 suitably supported and braced upon the lower side of the car platform. The lower end of the actuator is preferably provided with a shoe 36 within 55 which may be journaled if desired an anti-friction roller 37 adapted to engage, when projecting downwardly, the track plate 20, whereby any likelihood of the actuator being thrown into engagement with a cobble stone 60 or other obstacle will be avoided. To the upper end of the actuator is pivoted a link 38, having pivotal connection with the rearwardly extending lever 39 rigidly connected to a rock shaft 40. Each rock shaft is journaled 65 at the front end of the car platform,

and connected rigidly therewith and projecting upwardly within reach of the motorman is a hand-lever 41, whereby the motorman may have control of the actuator. In its normal position the actuator will be elevated 70 within its guide 35, the lever 41 connected therewith being in its upright or forward position. When it is desired for the motorman to change a switch, he will grasp the lever on that particular side of the car, causing the actuator to be projected downwardly into contact with the track plate 20 into the path of which the end of the contact member 15 will at that time be lying. The actuator shoe 36 will then be caused by the movement 75 of the car to engage such end of the contact member 15 causing the contact member to turn on its pivot 16, and such pivotal movement will be communicated to the T-lever by means of the connections 29. The arm 27 80 being a rigid part of the T-lever, the connection 28 will cause the desired movement of the switch, with a consequent corresponding indication by virtue of the switch blade 32 co-operating with such arm. 85

Any suitable counter-balancing means 90 may be employed in connection with the operating levers 41, such means indicated herein by springs 42 so connected with such levers as to tend to maintain them in normal position. Furthermore, there may be employed in connection with each of said levers a notched segment 43 in order to maintain such lever in any position of adjustment. 95

It is to be understood that slight specific 100 modifications of construction may be resorted to without departing from the spirit of this invention, as hereinafter claimed.

Any suitable materials may be employed in the construction, and the sizes and lengths 105 of the parts may be varied in accordance with specific requirements.

It will be understood that the actuator 28 may be shifted from one side of the arm 27 to the other in order to adapt the mechanism 110 for either a right or left switch.

Having thus described the invention, what is claimed as new, is:

1. In a device of the character described, the combination of a pivoted contact member having beveled ends and a series of holes, a switch including movable switch points, a T-lever pivoted between said switch points, a connector between the T-lever and the switch points, connections extending from certain 115 of the holes in the contact member to the T-lever, clamps adjustably connecting said connections with the T-lever, and means under the control of the motorman to cause movement of the contact member on its 120 pivot.

2. In combination with railway rails and switch points, of a T-lever having right and left members and a rearwardly extending bifurcated arm, a connector extending from 130

said arm to said switch points, an indicator switch box located between said rails, a switch blade pivoted therein, and having its end extending within the bifurcation of said

5 **T**-lever arm, and means under the control of the motorman to operate said **T**-lever, substantially as set forth.

In testimony whereof I affix my signature in presence of two witnesses.

CLARENCE E. MOODY.
